LAVATORY

Lendal R. Smith, San Jose, Calif.

Application September 24, 1937, Serial No. 165,535

5 Claims. (Cl. 4—10)

This invention relates generally to a lavatory and in particular relates to a lavatory which is designed for use in connection with modern bath rooms, in which it is desirable to conserve space 5 as well as provide a sightly arrangement of the facilities therein.

The principal object of my arrangement is to provide a lavatory arranged for normal enclosure in a cabinet or closet, but provided with drive 10 mechanism to slide the lavatory from the cabinet for use; the cabinet being preferably recessed in a wall, whereby the same and the enclosed lavatory are out of the way and not visible when the lavatory is not in use.

15 Another object of my invention is to provide an effective electric drive mechanism to advance the lavatory from or retract it into the enclosing cabinet.

An additional object of the invention is the 20 inclusion of automatically actuated control mechanism to open the flush water flow-valve with the advance of the lavatory from the cabinet and to close such valve with retraction of the lavatory. Thus, continuous flushing of the bowl, when the 25 lavatory is in use, is automatically accomplished.

A further object of the invention is to produce a simple and inexpensive device and yet one which will be exceedingly effective for the purpose 30 for which it is designed.

These objects I accomplish by means of such structure and relative arrangement of parts as will fully appear by a perusal of the following specification and claims.

35 In the drawings similar characters of reference indicate corresponding parts in the several views:

Fig. 1 is a side elevation of the device as enclosed within the cabinet.

Fig. 2 is a side elevation showing the lavatory 40 as advanced from the cabinet.

Fig. 3 is a diagrammatic illustration of the electric circuit employed.

Fig. 4 is an enlarged sectional view of the water flow valve.

45 Fig. 5 is a perspective view of the front of the cabinet and as arranged when the cabinet is enclosed in a wall.

Referring now more particularly to the characters of reference on the drawings, the device 50 comprises a bowl 1, preferably of the silent flush type, mounted on a suitable base 2 of box-like construction. The base is provided with small wheels 3 which ride on spaced, parallel tracks 4 secured to the floor 5 and extending into a cabinet 55 6, preferably recessed in a wall 7. The cabinet is

provided with doors 8 which are secured along their outer side edges to the cabinet by spring hinges 9 which normally maintain the doors in closed position, as shown in Fig. 5.

The bowl is provided with a rigid discharge 5 passage or duct 10 which projects from the rear of the base 2 and is connected to a sewer pipe 11 by means of a flexible tube 12, preferably a flexible metallic tube. This flexible tube 12 extends through a slot 13 cut in the floor from a point 10 adjacent the front of the cabinet to the rear thereof.

A water supply pipe 14 projects vertically into the cabinet adjacent one side thereof and is provided at its upper end with a valve casing 15 in 15 which is disposed a rotary plug valve 16. A flexible hose 17 leads from the outlet side of valve casing 15 to a water intake connection 18 on the rear of the bowl. The plug valve 16 is connected, on one side of the casing 15, to a radial arm 19 20 which is normally maintained in a valve closing position by a tension spring 20. A strike finger 21 is also secured to the rotary plug valve 16 and is normally in a depending position when the valve is closed under the influence of spring 21. 25 A cam arm 22 is mounted on the base 2 at its rear end and is adapted to engage finger 21 and open valve 16 upon advance of the lavatory from the cabinet and to separate from the finger and permit the valve to close upon retraction of the 30 lavatory into the cabinet.

The drive means to effect movement of the lavatory to and from the cabinet is constructed as follows:

Two pairs of spaced sprockets 23 are journaled 35 beneath the floor and underneath the cabinet, corresponding sprockets having shafts in common and which shafts are supported on spaced parallel frames 24. Each pair of sprockets is connected together by an endless chain 25, the chains 25 40 being disposed in substantially the plane of the sides of base 2. Arms 26 are connected to the sides of the base adjacent the rear thereof and extend through parallel slots 27 in the floor to fixed connection with the endless chains 25. A 45 reversible motor 28 drives the sprockets and endless chains by means of a drive belt B.

The circuit for the actuation of motor 28 comprises wires 29 leading from the power wires 30 to two terminals of the reversible motor. Other 50 wires 31 tap wires 29 and lead to a pair of the terminals of a four-terminal reversing switch 32 mounted on the front of the cabinet. Another wire 33 leads from a third terminal of the switch to one terminal of a spring blade switch 34 55

mounted in the rear of the cabinet. A wire 35 extends from the other terminal of switch 34 to the reversible motor 28. Another wire 36 connects the remaining terminal of switch 32 with 5 another spring blade switch 37 mounted adjacent the front of the cabinet. The switch 37 is in turn connected by wire 38 to the wire 35 leading to the reversible motor 28. A contact or cam arm 39 is fixed on base 2 and is so arranged as 10 to engage an insulated strike head 40 on switches 34 and 37 and to open the same when the lavatory reaches a fully retracted or fully advanced position respectively.

Operation

15 In normal position and when not in use, the lavatory is enclosed within the cabinet and the doors are closed; the two-way switch 32 then being in a closed position relative to wire 33, and 20 the switch 34 in an open position, as shown in Fig. 3.

To advance the lavatory from the cabinet, the reversing switch 32 is closed (relative to wire 36) to actuate the reversible motor in such direction 25 that with movement of chains 25 and attached arms 26, the base 2 and bowl 1 will be advanced from the cabinet for use; the motor 28 being stopped when arm 39 engages and opens switch 37 and after a predetermined advancing movement 30 has occurred.

When so advanced, the doors are swung apart and remain apart and in engagement with the base until the lavatory is retracted into the cabinet. Too, when the lavatory is advanced, a continuous flushing of the bowl will be effected, as 35 valve 16 will be automatically opened as hereinbefore described. The flexibility of tube 12 and hose 17 permits the lavatory to move as described without undue restriction.

40 The lavatory is returned to the cabinet by merely reversing the position of switch 32, causing a reversal of motor 28. When fully retracted, arm 39 opens switch 34 stopping the motor. Also, with such retraction, cam 22 moves away from 45 valve 16 and permits it to close and thus shut off the water supply to the bowl.

From the foregoing description it will be readily seen that I have produced such a device as substantially fulfills the objects of the invention as 50 set forth herein.

While this specification sets forth in detail the present and preferred construction of the device, still in practice such deviations from such detail may be resorted to as do not form a departure 55 from the spirit of the invention, as defined by the appended claims.

Having thus described my invention, what I claim as new and useful and desire to secure by Letters Patent is:

60 1. In combination, a cabinet, a lavatory nor-

mally disposed within the cabinet, means mounting the lavatory for sliding movement in and out of the cabinet, drive means to so move the lavatory, a water supply pipe adjacent the cabinet, a normally closed valve in said pipe, a flexible conduit connecting the supply pipe with the bowl of the lavatory and means operative upon movement of the lavatory out of the cabinet to open the valve and maintain the same open while the lavatory remains out of the cabinet. 5

2. A lavatory assembly comprising a cabinet, a toilet unit normally disposed in the cabinet, means mounting the toilet unit for sliding movement in and out of the cabinet, a water supply pipe disposed in the cabinet but out of the path of movement of the toilet unit, a normally closed valve for the pipe, a flexible conduit leading from the valve to the toilet unit, a valve control element on the valve exteriorly thereof, and a member mounted on the unit and arranged to engage and 10 actuate said valve control member upon movement of the unit from the cabinet. 15

3. An assembly as in claim 2 in which said valve control element comprises a radial lever, a spring connected with said lever and arranged 25 to normally hold the lever in a valve closing position, said member on the unit being disposed to engage said lever and move the same against the action of the spring to a valve opening position when the unit is advanced from the cabinet. 30

4. A lavatory assembly comprising a cabinet, a base member above the floor of the cabinet, a toilet bowl unit mounted on and rigid with the member, means mounting the member for sliding movement into and out of the cabinet, a fixed 35 sewer pipe below the floor of the cabinet terminating in an upwardly facing end disposed substantially midway of the length of the cabinet, and a flexible conduit connecting said end of the pipe and the toilet unit at the back; the floor of 40 the cabinet having an opening for the passage and flexing movement of the conduit.

5. A lavatory assembly comprising a cabinet, a base member above the floor of the cabinet, a toilet bowl unit mounted on and rigid with the member, means mounting the member for sliding movement into and out of the cabinet, a fixed 45 sewer pipe below the floor of the cabinet terminating in an upwardly facing end disposed substantially midway of the length of the cabinet, 50 the base member having depending sides, a discharge pipe rigid with and depending from the bottom of the bowl between the sides of the base member and extending rearwardly to a termination adjacent the rear end of the base member and above the floor of the cabinet and a flexible conduit connecting the ends of the pipes; the floor of the cabinet having an opening for the passage and flexing movement of the conduit. 55

LENDAL R. SMITH. 60
